UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

MEANS FOR SUPPORTING MEMBERS OF STALLS AND THE LIKE.

Specification of Letters Patent. Patented Aug. 24, 1915.

1,161,256.

Application filed February 16, 1914. Serial No. 818,951.

To all whom it may concern:

Be it known that I, HENRY L. FERRIS, a citizen of the United States, residing at Harvard, in the county of McHenry and State of Illinois, have invented a new and useful Improvement in Means for Supporting Members of Stalls and the like, of which the following is a specification.

My invention relates to certain new and useful improvements in means for supporting members of stalls, and the like, and is fully described and explained in the specification and shown in the accompanying drawings, in which:

Figure 1 is a side elevation of a stall embodying my improvement; Fig. 2 is a section through the lower part of the post and the construction particularly embodying my invention; Fig. 3 is a bottom plan of that part of the device attached to the post, and Fig. 4 is a top plan of that part of the device set in the concrete floor of the barn.

Referring to the drawings, it will be seen that in the floor of the barn is set a casting. This has a loop 5 adapted to give a special means for retention on the concrete, a channel-shaped socket 6, the upper surface of which is flush with the surface of the barn-floor, and overhanging flanges 7 at one end of the channel-shaped part 6, whereby the channel is restricted at one end. 8 is a post and it has attached to its lower end a hollow casting 9 having an L-shaped extension 10, provided with a rib 11 on its lower face to enter between the flanges 7. The extension 10 is perforated to receive a bolt 12, the head of which may be dropped through the enlarged part of the channel and slid along into the constricted part thereof.

When the bolt is in place, the casting 9 attached to the post is placed in position and the bolt tightened up, thus securing a tight fit between the parts. This structure is advantageous because the posts can be readily removed when desired, because the part set in the barn-floor lies flush with the surface of the floor, so as not to interfere with the

free use thereof when the post is not in position, and because the use of the arrangement shown diminishes the tendency of the post itself to corrode.

I realize that considerable variation is possible in the details of the construction herein shown, and I do not intend to limit myself thereto, except as pointed out in the following claims, in which it is my intention to claim all the novelty inherent in the device as broadly as is permitted by the state of the art.

I claim as new and desire to secure by Letters Patent:

1. In a device of the class described, in combination, a tubular metal post, a channel-shaped casting having a part provided with inwardly projecting flanges forming a constriction to receive and retain a bolt head, a casting provided on its lower face with a web to lie between the flanges and having an upwardly projecting cylindrical nipple provided with a reduced upper portion adapted to fit within the tubular metal post the bottom of said reduced portion forming a stop or bearing for the lower end of the post, said nipple being also provided with a lateral extension perforated to receive a bolt the head of which lies in the channel, as and for the purpose set forth.

2. A device of the class described comprising a channel adapted to be set in concrete and provided at one end with inwardly-extending flanges forming a constriction to receive and hold a bolt-head, a casting having a lateral extension perforated to receive a bolt, when held by the channel and its flanges, and provided on its lower face with a rib to lie between the flanges, said casting being adapted to be attached to the post to be supported, for the purpose set forth.

In testimony whereof I have hereunto set my hand this 4th day of February, 1914.

HENRY L. FERRIS.

In presence of two subscribing witnesses:

W. A. MUELLER,

A. LEADSITTER.
